INTERFOLDING MACHINE

James J. Deloye, Neenah, Wis., assignor to International Cellucotton Products Company, Chicago, Ill., a corporation of Delaware

Application January 27, 1944, Serial No. 519,895

8 Claims. (Cl. 164—68)

1

This invention appertains to interfolding machines and more particularly to a machine for cutting and folding thin, soft paper sheets, such as cleansing tissue. However, it is to be understood that the machine can be successfully used for cutting and interfolding other kinds of paper, such as, wax paper, crepe toweling, etc.

Such machines usually embody an upper sheet cutting mechanism and a lower sheet interfolding and stacking mechanism (see my prior Patent #2,116,782, issued May 10, 1938). Webs of paper are fed to the cutting mechanism and the webs are so cut that the resulting sheets are staggeredly arranged relative to one another, but in facing relation. A desired number of the interfolded sheets are packed in dispensing cartons and upon the withdrawal of one sheet from the carton, the next sheet follows so that it can be conveniently withdrawn from the carton.

When the sheets leave the cutting mechanism they are united at spaced points by bonds or connecting tabs, and hence the sheets are still, more or less, in the nature of a continuous web. This bond insures the proper travel of the sheets from the cutting mechanism to the interfolding mechanism. The withdrawal of a sheet from its carton is supposed to break this bond, but in actual practice, the bond often fails to break resulting in the withdrawal of more than one sheet from the carton. This is decidedly objectionable to the user. Where the cutting knives are dull and the sheets are not cleanly severed, this condition is greatly aggravated. Hence, it is highly advantageous that the bonds between the sheets be broken before the sheets are interfolded.

It has been proposed to sever the sheets straight across and to eliminate the bonds and to feed the sheets in close relation to the interfolding mechanism by rollers having pins which pierce the sheets, so that the sheets cannot get out of alignment or their proper close relation. However, the pin pricks in the sheets are objectionable, particularly with wax paper. In actual practice, the elimination of bonds is difficult due to the fact that the anvil insertion in the anvil rolls is made in sections (to permit adjustment and to prevent bowing of a long anvil insert) and where the sections meet, however close the arrangement, the paper will not be severed by the

2

knives at the meeting points of the anvil sections, resulting in the forming of bonds.

It is therefore, one of the primary objects of my present invention to provide a novel device arranged between the cutting mechanism and the interfolding mechanism for effectively breaking the bonds between adjacent sheets, whereby to insure the correct withdrawal of only one sheet at a time from the dispensing carton.

Another salient object of my invention is to provide a novel device which will receive the sheets from the sheet stripping and guiding members of the cutting mechanism and break the bonds and properly deliver the sheets in close edge to edge relation to the interfolding mechanism, the construction being such that the sheets will travel in a straight path from the cutting mechanism to the interfolding mechanism.

A further important object of my invention is to provide novel means for increasing the tension on the sheets at proper timed intervals for momentarily gripping the sheets and simultaneously exerting a pull on the sheets for breaking the bonds between the sheets.

25 A further important object of my invention is to provide a novel bond breaking mechanism which will receive the staggeredly arranged facing sheets from the cutting mechanism and simultaneously break the bond between the pairs of the staggeredly arranged sheets.

30 A still further important object of my invention is to provide a novel bond breaking mechanism which can be readily incorporated with an interfolding machine of the type shown in my mentioned patent without any material change thereto and which will operate efficiently and in proper timed relation to the cutting and interfolding mechanism thereof.

35 A still further object of my invention is to provide a bond breaking mechanism which will operate efficiently with the interfolding mechanism shown in my mentioned patent or rotary interfolding mechanism of the type shown in the Christman patent, #1,761,517, issued June 3, 1930.

40 45 With these and other objects in view, the invention consists in the novel construction, arrangement, and formation of parts as will be hereinafter more specifically described, claimed and illustrated in the accompanying drawings, in which drawings:

Figure 1 is a fragmentary, vertical, sectional view illustrating my novel bond breaking mechanism incorporated with a sheet cutting and interfolding mechanism, the cutting mechanism shown being of the type illustrated in my mentioned patent and the interfolding mechanism being of the type shown in the Christman patent.

Figure 2 is a fragmentary, side, elevational view of my interfolding machine with the novel bond breaking mechanism, the view illustrating the drive for the bond breaking mechanism.

Figure 3 is a plan view of one of the cutting rolls with parts thereof broken away and in section, to illustrate structural detail.

Figure 4 is a transverse, sectional view through the cutting roll taken on the line 4—4 of Figure 3 looking in the direction of the arrows illustrating my adjusting mechanism for the cutting knives.

Figure 5 is a fragmentary, longitudinal, sectional view through the cutting roll taken on the line 5—5 of Figure 4 looking in the direction of the arrows, illustrating the novel mechanism for individually adjusting the knives.

Figure 6 is a transverse, sectional view through one of the anvil rolls taken on the line 6—6 of Figure 7, looking in the direction of the arrows.

Figure 7 is a fragmentary, plan view of one of the anvil rolls.

Figure 8 is a vertical, sectional view taken on the line 8—8 of Figure 1, looking in the direction of the arrows illustrating a part of my novel bond breaking mechanism.

Figure 9 is a fragmentary, detail, sectional view taken on the line 9—9 of Figure 2 looking in the direction of the arrows illustrating one of the outer guide rolls for the guide belts for the sheets.

Figure 10 is an enlarged, fragmentary, detail, transverse, sectional view through the bond breaking mechanism, the section being taken on the line 10—10 of Figure 9 looking in the direction of the arrows, the sheet stripping and guiding members of the sheet cutting mechanism being omitted to illustrate clearly the arrangement of the guide belts and the rolls of the bond breaking mechanism.

Figure 11 is an enlarged, fragmentary, detail, sectional view taken on the line 11—11 of Figure 8 looking in the direction of the arrows illustrating the resilient mounting of one of the upper feeding and tension rolls of the bond breaking mechanism.

Figure 12 is an enlarged, fragmentary, plan view of a pair of adjacent paper sheets illustrating the bond between the sheets.

Figure 13 is a view similar to Figure 1, but showing the type of interlocking mechanism utilized in my prior patent, instead of the rotary interlocking mechanism shown in Figure 1.

Referring to the drawings in detail, wherein similar reference characters designate corresponding parts throughout the several views, the letter I generally indicates my improved interlocking machine and this machine embodies an upper cutting mechanism C, a lower interlocking and stacking mechanism S and the novel intermediate bond breaking mechanism T.

As stated, the cutting mechanism C is of the same general character as shown in my prior patent and hence this mechanism will not be described in minute detail. At this point, however, it is to be noted that certain improvements in the cutting rolls have been made, as will be later set forth.

The cutting mechanism C embodies a frame

15 in which is journaled a pair of like cutting rolls 16 and 17 and a pair of like anvil rolls 18 and 19. The cutting roll 17 cooperates with the anvil roll 18 while the cutting roll 16 cooperates with the anvil roll 18 and the surface speed of all of these rolls is equal. It is to be noted that the anvil rolls 18 and 19 are arranged in facing relation, while the cutting rolls 16 and 17 are spaced with their longitudinal axis spaced a greater distance from the transverse center of the frame than the axis of the anvil rollers 18 and 19 so that the cutter rolls will not contact. A web of paper 20 is fed over the anvil roll 19 between this roll and the cutter roll 17 by guide and feeder rolls 21. A similar web of paper 22 is fed between the cutter roll 16 and the anvil roll 18 by guide and feeder rolls 23. The webs 20 and 22 are slit longitudinally by slitter knives 24 and 25.

Thus it can be seen that the webs 20 and 22 are first cut and are then fed downwardly between the anvil rolls 18 and 19. The relation of the rolls 17 and 19 to the rolls 16 and 18 is such that when the web 20 is being cut by the rolls 17 and 19, the rolls 16 and 18 will not be cutting the web 22, and consequently, as the sheets are fed down between the rolls 18 and 19, the cut sheets will be staggeredly related.

Referring specifically to the cutting rolls 16 and 17, it can be seen that each embodies a cast iron or like body 26 keyed or otherwise fastened respectively to drive shafts 27 and 28. Each one of the bodies 26 has formed on its opposite sides longitudinally extending slotted ribs 29 in which are fitted sectional paper cutting knives 30. The sections of the knives are held against outward movement by adjustable blocks 31 and set screws 32 are provided for adjusting these blocks. Each section of the cutting knives is supported on a pair of cams 33 which are formed on or secured to cam shafts 34 rotatably mounted transversely in the ribs 29. The outer ends of the cam shafts are provided with polygonal heads 35 whereby the same can be conveniently turned so as to adjust the position of the cams 33 against the knife sections 30 whereby the sections can be accurately adjusted relative to themselves and to the anvil roll. The cam shafts 34 can be held in an adjusted position by means of nuts 36 threaded on the cam shafts and obviously these nuts can be threaded into binding contact with the ribs 29. Hence, by adjusting the blocks 31 and the cam shafts, fine accurate settings of the knife sections are insured. By having the knives in sections, a long continuous knife is eliminated and it has been found that in using a long knife, the same has a tendency to bow and accurate adjustment throughout its entire length is difficult.

The anvil rolls 18 and 19 are also identical in construction and each include a cylindrical body 37. The bodies 37 of the anvil rolls 18 and 19 are keyed or otherwise secured respectively to their drive shafts 38 and 39. Each cylindrical body 37 of the anvil rolls is provided on opposite sides with longitudinally extending grooves 40 in which are fitted sectional anvil blocks 41 which can be formed of tool steel. These blocks can be held in place in any desired way, such as by the use of set screws 42. After the anvil blocks are fitted in place, the outer faces thereof are honed perfectly smooth with the outer face of the anvil roll bodies 37. These anvil blocks are placed with their ends in close relation and by having anvil blocks in lieu of a continuous anvil strip, bowing of such a strip is eliminated.

The cut sheets travel down between the facing

anvil rolls 18 and 19 through the bond breaking mechanism T to the interlocking mechanism S.

In view of the fact that anvil blocks 41 are utilized instead of a continuous anvil strip, the paper webs will not be severed completely across, but will be united by bonds or tabs at the points where the anvil blocks abut one another. This is due to the fact that the knives 30 will not cut clean through the webs at the points where the anvil blocks 41 abut, due to the slight space between the blocks, and the knives not bearing on the anvil blocks at these spaces, cannot make a complete cut.

The interlocking mechanism S has been shown to be of the rotary type and can be considered as of the same construction shown in the Christman patent mentioned. However, I do not limit myself to the exact construction shown in the Christman patent, as other types of rotary interlocking mechanism can be employed, such as that shown in the Campbell Patent, #1,871,301, issued August 9, 1932, or the Brown et al. patent, #1,219,239, issued March 13, 1917. In lieu of providing the rotary interlocking mechanism, I can utilize an interlocking mechanism D (see Figure 13) of the same type as shown in my mentioned patent.

As the rotary interlocking mechanism S is the same as the Christman patent, the same will not be described in detail, but it is to be noted that the same includes a supporting frame 43 in which is rotatably mounted the interlocking rollers 44 and 45 and strippers 46 receive the interfolded sheets from the rolls. The rolls are keyed or otherwise secured respectively to shafts 47 and 48.

Now referring specifically to my novel bond breaking mechanism T, it will be noted that the same includes a frame 49 and this frame is securely fastened to the frames 15 and 43 so that a single unitary machine is provided. Obviously, the frames 15, 43, and 49 can be made as a single unit. In other words, independent frames 15, 43, and 49 do not have to be provided. The novel bond breaking mechanism also includes a pair of upper facing top guide and pressure rolls 50 and 51 and these rolls are keyed or otherwise secured respectively to shafts 52 and 53. The shafts are journaled in suitable bearings carried by the frame 49 and either one, or both of the shafts, can be mounted so that the rolls 50 and 51 can move relative to one another. As shown, the shaft 53 has its bearing blocks 54 slidably mounted and springs 55 engage the bearing blocks so as to normally urge the bearing blocks and the roll 51 toward the roll 50. These rolls 50 and 51 have knurled faces for engaging the paper sheets and the rolls are normally so spaced that the sheets will not be gripped by the rolls with tension. Hence the points on the peripheries of the rolls will engage the sheets to feed the same downwardly. The rolls are normally spaced the correct distance by cam discs 56 and 57 which are fastened to the shafts 52 and 53. The peripheries of the cam discs 56 and 57 have cam indentations 58 formed in their peripheries. Hence, when these indentations meet, the springs 55 will function to force the roll 51 toward the roll 50 and the paper sheets will be momentarily gripped by the rolls 50 and 51.

Arranged below the guide and gripping rolls 50 and 51 are the bond breaking rolls 59 and 60 and these rolls have formed on their peripheries sheet gripping and pulling lugs 61 and these lugs 61 meet to grip and pull the sheets at the exact time the cam indentations 58 on the discs 56 ride

into contact. The bond breaking rolls 59 and 60 are keyed or otherwise secured respectively to shafts 62 and 63 and these shafts are journaled in suitable bearing blocks 64 mounted on the frame 49. By referring to Figures 1 and 10, it can be seen that the facing sheets are fed straight downwardly between the rolls 50 and 51, the rolls 59 and 60 to the feed rolls 65 and 66 which deliver the sheets to the rotary interlocking mechanism S. The feeding rolls 65 and 66 are keyed or otherwise secured to shafts 67 and 68 mounted in bearing blocks 69.

The sheets are efficiently guided and held straight in their travel through the bond breaking mechanism T by a series of belts 10 and these belts are received in grooves formed in the rolls 50 and 51, the rolls 59 and 60, and the rolls 65 and 66. The guide belts 10 are also received in grooves formed in guide rolls 71 and 72. These rolls 71 and 72 are mounted on opposite sides of the bond breaking rolls and are keyed or otherwise secured to shafts 73 and 74 rotatably mounted in suitable bearings carried by the frame 49.

All of the mentioned rolls of the bond breaking mechanism are driven at the same speed of rotation but substantially twice as fast as the cutting and anvil rolls. The circumference of the anvil rolls is twice the circumference of the rolls of the bond breaking mechanism so that the surface speed of the rolls of the bond breaking mechanism is the same as that of the cutter rolls and the same as the speed of travel of the webs.

The cutting mechanism C also includes paper stripping and guide means 75 and this means is identical in construction with the means numbered 115 to 124 in the mentioned Deloye patent. The rolls 50 and 51 of the bond breaking mechanism are also provided with grooves 76 which receive the depending fingers 77 of said guide means 75.

Paper stripping and guide fingers 78 are also provided for the rolls 65 and 66 and these rolls 65 and 66 are also provided with grooves 79 for receiving the guide fingers 78. The fingers 78 extend down toward the interlocking rolls 44 and 45 and insure the proper delivery of the cut paper sheets to said interlocking rolls.

In Figure 2 I have illustrated one preferred type of mechanism for driving the various parts of the cutting, interlocking, and bond breaking mechanism in timed relation relative to one another. This drive mechanism includes a main drive shaft 80 which can be driven from a chain 81 or the like 81 from a drive motor (not shown). The shaft 80 has keyed or otherwise secured thereto a pair of sprocket wheels 82 and 83 and the sprocket wheel 82 has trained thereabout a drive sprocket chain 84 leading up to the cutting mechanism. The sprocket wheel 83 has trained thereabout a drive sprocket chain 85 which is trained over a sprocket wheel 86 keyed or otherwise secured to the shaft 48 of the interlocking mechanism. The shafts 47 and 48 are driven at the same speed through intermeshing gears 87 and 88 keyed or otherwise secured respectively to said shafts 47 and 48. Consequently, the interlocking mechanism S is driven from the drive shaft 80. Fastened to the shaft 39 of the anvil roll 19 is a relatively large sprocket wheel 88 and the chain 84 leading from the drive shaft 80 is trained around said sprocket wheel 88. All of the shafts 27, 28, 38 and 39 have keyed thereto gear wheels 89 of equal diameter and the gear wheels 89 of the shafts 38 and 39 intermesh so

that the roll 18 will be driven from the roll 19. The gears of the shafts 28 and 39 intermesh and hence the cutting roll 17 will be driven from the shaft 39. The gears of the shafts 27 and 38 intermesh and consequently the cutting roll 16 will be driven from the roll 38. The shafts 53, 63, 68 and 74 of the bond breaking mechanism have keyed thereto sprocket wheels 90 and these sprocket wheels are all of the same diameter and have trained thereabout a drive sprocket chain 91. The shafts 52, 62, 67, and 73 of the bond breaking mechanism all have similar sprocket wheels 92 keyed thereto and these sprocket wheels have trained thereabout a drive sprocket chain 93. The shafts 73 and 74 have also keyed thereon respectively sprocket wheels 94 and 95. The sprocket wheel 94 has trained thereabout a drive sprocket chain 96 which is also trained over a sprocket wheel 97 keyed to the shaft 38 of the cutting mechanism. The sprocket wheel 95 has trained thereabout a drive sprocket chain 98 which is also trained over a sprocket wheel 99 keyed to the shaft 39 of the cutting mechanism.

From the foregoing, the drive for the various parts of the machine will be clear and all of the parts are driven in proper timed relation. The drive for the paper webs 20 and 22 and the drive for the slitting mechanism has not been described as the same are driven in an identical manner with the Deloye patent.

In operation of my novel interlocking machine the paper webs 20 and 22 are fed over the cutting rolls 18 and 19 and the webs are alternately cut and the staggeredly arranged facing sheets are fed between the rolls 18 and 19 down to the bond breaking mechanism T. When the low parts 58 of the cam discs 56 and 57 of the uppermost rolls 50 and 51 register with each other, the spring mounted roll 51 will move inwardly toward the roll 50 and the sheets will be momentarily gripped. At this time the pulling ribs 61 (see Figure 10) of the intermediate rolls 59 and 60 will be brought toward one another into pulling contact with the sheets and the sheets will be pulled down and the bonds in the web portions extending from the pair of rolls 50 and 51 to the pair of rolls 59 and 60 will be broken due to the web pulling effect of the lugs or ribs 61 which have a surface speed slightly greater than the surface speed of the rolls 50 and 51 and the bottom rolls 59 and 60. This additional surface speed of the breaker roll ribs 61 is, of course, due to the relatively increased radius of the said rib portions of the breaker rolls.

It will be seen that each time that the pulling rolls grip the webs, each of the webs will have a line of severance with its interrupting bonds located in the web length between the upper roll pair and the breaker roll pair. This follows from the above explained relationship between the speeds and sizes of the cutting rolls and bond breaking mechanism rolls. In Fig. 10, a line of severance in the web 20 is indicated at 20a and a line of severance in the web 22 is indicated at 22a. Since the intermediate rolls 59 and 60 make one turn for each sheet length between successive lines of severance, the bond breaking operation will repeatedly occur when lines of severance are in the positions of the lines 20a and 22a. Hence, it will be seen that each bond breaking operation simultaneously breaks the bonds in two relatively staggered lines of severance and stretching of the web material is avoided.

Incident to the breaking of the bonds, the

sheets below the rolls 59 and 60 will be slightly rippled due to the increased surface speed of the lugs. This is hardly noticeable to the eye, but is advantageous to the successful operation of the machine in that edge to edge abutting relation of the severed sheets is insured. The severed sheets are now continuously fed down by the rolls 65 and 66 to the interlocking mechanism S where the same are stacked by the stripping mechanism 46. The interlocked sheets can now be packed in the cartons.

With my invention, the sheets are completely separated from one another and hence one sheet can be easily withdrawn from the carton without danger of withdrawing another sheet therewith. However, due to the fact that the sheets are interlocked, as one sheet is drawn from the carton, the adjacent sheet will be positioned for convenient withdrawal.

In Figure 13 I have shown the interlocking mechanism D which, as stated, is of the same type as shown in my prior patent and hence this interlocking mechanism D will not be described in detail. It is to be noted, however, that this mechanism includes gripping jaw sets 100 and 101 and cooperating tucker blades 102 and 103. The gripping jaws 100 and 101 travel in elliptical paths. The view has been shown so as to clearly bring out the fact that my novel bond breaking mechanism T can be successfully used with various types of interlocking mechanisms.

Changes in details may be made without departing from the spirit or the scope of my invention, but what I claim as new is:

1. In a paper sheet interlocking machine, a sheet feeding and bond breaking mechanism comprising a pair of sheet feeding and gripping rolls and a pair of bond breaking rolls, means for driving said rolls at the same speed, means normally urging at least one of the first mentioned rolls toward the other, discs on said first mentioned pair of rolls normally holding said rolls spaced for feeding sheets, said discs having cam indentations whereby upon aligning of said indentations the rolls will momentarily grip said sheets, and peripheral bond breaking lugs on said second mentioned pair of rolls for engaging said sheets at the same time the indentations on the discs align.

2. In a paper sheet interlocking machine, a mechanism for feeding sheets and for breaking bonds between the sheets including an upper pair of sheet feeding and gripping rolls, a lower pair of sheet feeding rolls, and an intermediate pair of sheet engaging rolls, means for driving all of said rolls at the same speed, means normally urging at least one of said upper rolls toward the other roll, discs on said upper rolls normally holding the upper rolls spaced for properly feeding the sheets, said discs having cam indentations adapted to meet for permitting said rolls to momentarily grip the sheets, and radially extending peripheral paper pulling and breaking lugs on the intermediate rolls adapted to engage the sheets at the same time the upper pair of rolls grip the sheets.

3. In a paper sheet interlocking machine, a mechanism for feeding sheets and for breaking bonds between the sheets including an upper pair of sheet feeding and gripping rolls, a lower pair of sheet feeding rolls, and an intermediate pair of sheet engaging rolls, means for driving all of said rolls at the same speed, means normally urging at least one of said upper rolls toward the other roll, discs on said upper rolls normally

holding the upper rolls spaced for properly feeding the sheets, said discs having cam indentations adapted to meet for permitting said rolls to momentarily grip the sheets, and radially extending peripheral paper pulling and breaking lugs on the intermediate rolls adapted to engage the sheets at the same time the upper pair of rolls grip the sheets, and paper feeding belts trained about said rolls, said rolls having peripheral grooves for receiving the belts, and said belts having abutting vertical runs for engaging the sheets.

4. In a machine of the class described, mechanism for almost completely transversely severing a paper web at longitudinally spaced intervals, means for feeding the web to said severing means including a cutting roll having a longitudinal groove, sectional cutting knives fitted in the groove, and means for independently adjusting the sections of the knives radially of the rolls including rotatable cams engaging the inner edges of the sections of the knives.

5. In a machine of the class described, mechanism for almost completely transversely severing a paper web at longitudinally spaced intervals, means for feeding the web to said severing means including a cutting roll having a longitudinal groove, sectional cutting knives fitted in the groove, and means for independently adjusting the sections of the knives radially of the rolls including rotatable cams engaging the inner edges of the sections of the knives, and means for locking the cams in an adjusted position.

6. In a machine of the class described, means for transversely partially severing a pair of paper webs in such a manner as to divide the webs into a series of sheet areas having interconnecting bonds, means for continuously feeding said partially severed paper webs into face-to-face relation with the lines of severance and bonds in one web in staggered relation to the lines of severance and bonds in the other and continuing the travel of said webs in said face-to-face relation, and bond-breaking mechanism comprising a pair of web guiding and holding rolls driven at the same surface speed as the speed at which said webs are fed, web feed accelerating means adapted to receive said webs from said rolls and spaced therefrom a distance in excess of the distance between the succeeding staggered lines of severance in said face-to-face webs but less than the distance between successive lines of severance in the respective webs, said web feed accelerating means comprising web gripping means driven so as to cause the web portions gripped thereby to travel at a higher speed than the normal speed of travel of said webs, said web gripping means being timed to grip and accelerate the travel of said webs when there is a line of severance and bonds in each of the webs within the web length extending from said holding rolls to said accelerating means, thereby to simultaneously break the bonds in a pair of staggered lines of severance in said webs, and a pair of web feeding rolls for receiving said webs from said web feed accelerating means and continuing the feed of said web at the same speed as said first mentioned web feeding means.

7. In a machine of the class described, means for transversely partially severing a pair of paper webs in such a manner as to divide the webs into a series of sheet areas having interconnecting bonds, means for continuously feeding said partially severed paper webs into face-to-face relation with the lines of severance and bonds in one

5 web in staggered relation to the lines of severance and bonds in the other and continuing the travel of said webs in said face-to-face relation, and bond-breaking mechanism comprising a pair of web guiding and holding rolls driven at the same surface speed as the speed at which said webs are fed, roll spacing means normally holding said rolls in such spaced relation as to prevent the application by said rolls of substantial pressure on said webs and operative, once in each turn of said rolls, to cause the same to momentarily grip said webs so as to prevent slippage thereof between said rolls, web feed accelerating means adapted to receive said webs from said rolls and spaced therefrom a distance in excess of the distance between the succeeding staggered lines of severance in said face-to-face webs but less than the distance between successive lines of severance in the respective webs, said web feed accelerating means comprising web gripping means driven so as to cause the web portions gripped thereby to travel at a higher speed than the normal speed of travel of said webs, said roll spacing means and web gripping means being respectively timed to simultaneously grip said webs and to accelerate the travel thereof when there is a line of severance and bonds in each of the webs within the web length extending from said holding rolls to said accelerating means, thereby to simultaneously break the bonds in a pair of staggered lines of severance in said webs, and a pair of web feeding rolls for receiving said webs from said web feed accelerating means and continuing the feed of said web at the same speed as said first mentioned web feeding means.

40 8. In a machine of the class described, means for transversely partially severing a pair of paper webs in such a manner as to divide the webs into a series of sheet areas having interconnecting bonds, means for continuously feeding said partially severed paper webs into face-to-face relation with the lines of severance and bonds in one web in staggered relation to the lines of severance and bonds in the other and continuing the travel of said webs in said face-to-face relation, and bond-breaking mechanism comprising a pair of web guiding and holding rolls driven at the same surface speed as the speed at which said webs are fed, roll spacing means normally holding said rolls in such spaced relation as to prevent the application by said rolls of substantial pressure on said webs and operative, once in each turn of said rolls, to cause the same to momentarily grip said webs so as to prevent slippage thereof between said rolls, rotary web feed accelerating means adapted to receive said webs from said rolls and spaced therefrom a distance in excess of the distance between the succeeding staggered lines of severance in said face-to-face webs but less than the distance between successive lines of severance in the respective webs, said web feed accelerating means comprising a pair of oppositely rotating members having cooperating web gripping portions rotated so as to cause said web gripping portions to travel at a higher speed than the normal speed of travel of said webs, said roll spacing means and web gripping portions being respectively timed to simultaneously grip said webs and to accelerate the travel thereof when there is a line of severance and bonds in each of the webs within the web length extending from said holding rolls to said accelerating means, thereby to simultaneously break the bonds in a pair of staggered lines of severance in said webs, and a pair of web feeding rolls for receiving said

11

webs from said web feed accelerating means and continuing the feed of said web at the same speed as said first mentioned web feeding means.
